UNITED STATES PATENT OFFICE.

JOHN W. ANDERSON, JR., OF WOODLAND, ILLINOIS.

RAILWAY-SIGNAL.

SPECIFICATION forming part of Letters Patent No. 759,652, dated May 10, 1904.

Application filed February 20, 1903. Serial No. 144,281. (No model.)

To all whom it may concern.

Be it known that I, JOHN W. ANDERSON, JR., a citizen of the United States, residing at Woodland, in the county of Iroquois and State 5 of Illinois, have invented a new and useful Railway-Signal, of which the following is a specification.

This invention relates to certain improvements in railway-crossing alarms and signals

10 of similar character, wherein an electromagnetic-bell or other alarm is sounded at a crossing or station on the approach of a train in either direction.

The principal object of the invention is to 15 provide an improved form of signaling mechanism which will occupy but small space and will act effectually in sounding an alarm at the desired point from an approaching train, a further object being to provide a simple 20 form of mechanism which will prevent the sounding of the alarm by a train receding from the crossing or other point where the alarm is situated.

With these and other objects in view the invention consists in the novel construction and arrangement of parts hereinafter described, illustrated in the accompanying drawings, and particularly pointed out in the appended 25 claim.

30 In the drawings, Figure 1 is a plan view of a device for closing an alarm-circuit, a portion of a railway-line, and the circuits extending between the line, and the circuit-closing device being illustrated in diagram in order that

35 the operation of the device forming the subject of the invention may be clearly understood. Fig. 2 is a detail view of the two interlocking armature-arms for preventing the closing of the alarm-circuit by a receding 40 train. Fig. 3 is a detail perspective view of one of the arms. Figs. 4, 5, 6, and 7 are diagrams illustrating the positions assumed by the armature-arms when the circuits are successively deenergized.

45 Similar numerals of reference are employed to indicate corresponding parts throughout the several figures of the drawings.

The device comprises in general a pair of relays connected in circuits extending from 50 the railway-sections on opposite sides of the

crossing or other point where the alarm is situated, both relays being adapted to close a local circuit including an alarm and a source of electrical energy, and the relay-armatures being adapted to interlock, so that when one 55 is actuated by an approaching train it will prevent the closing of the circuit by the second relay after the train passes and is receding from the crossing.

Referring to the drawings, 1 and 2 designate 60 a pair of relay-magnets arranged closely together and in the same plane, the relays being comparatively small and placed as near to each other as possible in order that they may occupy but little space, devices of this class 65 being usually inclosed in a box or casing and secured to a post adjacent to the crossing or station. To the fixed frames of the relays are pivoted armatures 3 and 4, respectively, and in the construction shown in Fig. 1, where the 70 relays are normally energized, the armatures rest against insulated back-stops 5 against the stress of curved springs 6, extending between securing-screws 7, secured, respectively, to the fixed frame and the armatures, the screws 75 passing through bent portions of the springs, so that by tightening or loosening the screws the stress of the springs may be adjusted to any desired extent.

The back-stops 5 are carried by one arm of 80 a U-shaped bar 8, and in the opposite arm of each bar is an adjustable screw 9, forming an outer stop for limiting the outward movement of the armature.

The two stops 9 are connected by a line-wire 85 10 to a local alarm 11 and one pole of a local battery 12, the opposite pole of the battery being connected by a line-wire 13 to the relay-frames and through the frames to the armatures, so that when either armature moves 90 into contact with one of the stops 9 the local circuit will be closed and the alarm will be sounded.

14 and 15 designate two sections of a railway-line located on opposite sides of the crossing or station and insulated from each other. The traffic-rails 14 are connected in a closed circuit including a battery 16 and a relay 1, while the traffic-rails of the section 15 of the track are connected in a closed circuit includ- 100

ing a battery 17 and the relay 2, so that on the approach of a train in either direction the circuit through the relays will be closed through the rolling-stock and short-circuited, 5 the springs 6 then acting to move the relay-armatures into contact with the stops 9 and close the local alarm-circuit.

The mechanism thus far described will be operated by a train approaching the crossing 10 or station in either direction; but in order to render the device effective for practical purposes it is necessary to provide means for preventing a train after sounding an alarm on its approach to the crossing from sounding a 15 second alarm after leaving the crossing and at the same time leaving the system free for the sounding of an alarm by a following train approaching the crossing in the same direction. This is accomplished by a pair of interlocking arms 21 and 22, secured, respectively, to the armatures 3 and 4 of the relays 1 and 2. The arm 21 is rigidly secured at one end to the armature 3 and at the opposite end is bent rearwardly and outwardly, as indicated at 23, the angularly-bent portion being approximately on the arc of a circle struck from the pivot-point of the armature 3. A portion of the end of the arm 21 and the major portion of the angularly-bent arm 23 are 20 cut away or recessed, as shown more clearly in Fig. 3, the width of the arm being reduced about one-half and interfitting with the similar end portion of the arm 22. The extreme end of both arms are of the full width of the 25 strip of metal which forms the arms, and both are slightly curved, as indicated at 24, to form lugs for engagement with the opposite arm.

The normal position of the parts is that indicated in Figs. 1 and 2, the curved and reduced portions of the arms overlapping and both arms being free to move in the event of the deenergizing of either relay. If the relay 1 is deenergized by the approach of a 30 train in the direction of the arrow, Fig. 1, the arm 21 will move to the dotted-line position shown in Fig. 2, or to the full-line position shown in Fig. 5, until the armature makes contact with the adjustable stop 9 and closes 35 the local alarm-circuit. The parts will remain in the position shown in Fig. 5 until the train passes the crossing and enters on the portion 15 of the track, when the circuit will be closed through the rolling-stock and the relay 2 deenergized. Both relays are deenergized during the time the train is passing the crossing 40 and the arms 21 and 22 assume the position shown in Fig. 6, the lug 24 at the end of the arm 22 engaging the angular portion 23 of the arm 21 and movement of the armature 4 to circuit-closing position being prevented. When the train fully leaves the section 14 of the track, the circuit is again established and 45 the relay 1 is energized, its armature-lever moving to the position illustrated in Fig. 7,

but the lugs 24 of the arms being still engaged and preventing movement of the armature 4 to circuit-closing position while the relay 2 is deenergized. The position of the parts is such that should a following train enter the section 14 of the trackway the relay 1 will be deenergized and the relay-armature will be free to again move to the positions shown in Figs. 5 and 6 and close the local alarm-circuit. When the train finally leaves 75 the section 15 of the trackway, both relays are energized and return to the position shown in Fig. 4.

The closed-circuit system herein described and illustrated in Fig. 1 is in many respects 80 the best system for use in connection with an alarm of this character, as in the event of the failure of either of the batteries 16 or 17 or the breaking of a wire or short-circuiting 85 from any cause the relays will be deenergized and the local alarm-circuit closed, the alarm being sounded continuously until the line is repaired.

By arranging the relays closely together and in the same plane they occupy but little 90 space and may readily be secured within a comparatively small box or casing, which may also contain the local alarm or the electromagnets and armatures of such alarm.

While the construction herein described 95 and illustrated in the accompanying drawings is the preferred form of the device, it is obvious that various changes in the form, proportions, size, and minor details of the structure may be made without departing from the 100 spirit or sacrificing any of the advantages of the invention.

Having thus described my invention, what I claim is—

In a device of the class specified, a railway-line divided into insulated sections or blocks, relays, normally closed electric circuits including the track-sections and relays, armatures pivotally mounted on the relay-frames, insulated back-stops against which said armatures are held while the relays are energized, circuit-closing stops with which the armatures make contact when the relays are deenergized, an armature-controlled local alarm-circuit connected to the stops and including an alarm and a source of electrical energy, arms 21 and 22 secured respectively to the armatures and each provided with interengaging end portions arranged approximately on curved lines struck from the pivotal centers of the armatures, the engaging portions of the arms being reduced in width and each being provided with a lug 24, substantially as specified.

In testimony that I claim the foregoing as my own I have hereto affixed my signature in the presence of two witnesses.

JOHN W. ANDERSON, JR.
